ENGINE COOLING SYSTEM

Albert Lewis MacClain, Manchester, Conn., assignor, by mesne assignments, to United Aircraft Corporation, a corporation of Delaware

Application July 8, 1932, Serial No. 621,425

8 Claims. (Cl. 123—171)

This invention relates to an improvement in aircooled internal combustion engines and is shown applied on a type of engine adapted to be used in aircraft.

5 It has been found that as the power output of internal combustion engines is increased and these engines encased in cowls to reduce their air resistance the difficulty of properly cooling the engine is likewise increased and especially is this true of multiple row aircooled engines. A point is finally reached at which the conventional structures do not provide sufficient cooling.

10 An object of this invention is to provide means to assist in cooling internal combustion engines.

15 Further and other objects and advantages will be apparent from the specification and claims and from the accompanying drawings which illustrate what is now considered the preferred embodiment.

20 Figure 1 is a partial front elevation of the engine partly in section and with certain of the cylinders and other parts removed to better show the baffle structure.

25 Figure 2 is a developed section showing one front and two rear cylinders.

Figure 3 is a diagrammatic side view partly in section with many of the engine parts omitted.

30 Figure 4 is a developed section showing two front and one rear cylinder with a modified form of baffle retainer.

Figure 1 shows a radial engine of the aircooled type having a crankcase 16, a propeller hub 18 and 14 cylinders indicated by numerals 1 to 14 inclusive. Cylinders 1, 2, 12 and 14 have been omitted to more clearly show the air deflecting means. A cowl, 20, of any suitable type surrounds the engine. This cowl is preferably of the type called "low drag" cowls and which is adapted to reduce the drag of the engine. This 35 cowl is also preferably of the one piece split type in which the ring forming the cowl is split from the front to the rear edge and drawn together by means of turn buckles which draw the cowl tightly onto the felt pads 22, which are placed between the cowl and the rocker box covers, thus holding the cowl in place on the engine. In the embodiment shown the cowl is open at the front and rear but if desired a perforated nose cowl may be used to partially close the front of the ring cowl.

40 It has been found that even if as much air as possible is allowed to pass under the cowl and around and between the engine cylinders there may be times during which the temperature of the engine may rise beyond desirable limits. If, 45 however, the air flow is restricted as by placing

baffles between the cylinders and between the rocker boxes it has been found that a material improvement in the cooling results.

It has also been found that this restricted air-flow in addition to giving a material improvement 5 in the cooling also increases the airplane speed. This increase in speed is probably due to a reduction in the drag of the engine and cowl.

In the embodiment shown in the drawings baffles 24 and 26 are placed between the cylinders 10 thereby blocking the space between the front and rear cylinders except for the space between the individual cooling fins. These baffles are made V shaped and follow the contour of the outside edges of the fins as closely as practicable. They 15 also extend to a point as close to the crankcase of the engine as is practicable and they may extend to the cowl but in order to make the rocker boxes more accessible for adjustments when the cowl is removed the baffles may stop short of the 20 cowl and join baffles 32 and 34 which are fastened to the cowl and in effect, form extensions of the baffles 24 and 26. The baffles 24, 26, 32 and 34 thus form deflectors which close the space between the cylinders as nearly as is practicable. 25 The baffle 24 is held in place in the modification shown in Figures 1 and 2, by means of a bolt 36, which passes through a suitable hole in the baffle and is connected with a spring 40. By tightening the wing nut 38 the baffle and the spring 40 30 are drawn toward each other and securely wedged between the two cylinders. The baffles are provided with the bosses 42 which bear on the cylinder fins and which bring the point of support of the baffles far enough around on the cylinder fins so that expansion and contraction of the cylinder or baffle will not cause the baffle to be tightly wedged between the cylinders and perhaps force them apart. If any such action should attempt 35 to take place the supports 42 would slide on the engine fins and perhaps create a little change in the tension of the spring 40 which acts as a sort of a flat spring. The supports 42 may rest on the outside edges of the fins as shown in Figure 2, in 40 which case the contour of the outside of the fins prevents longitudinal movement of the baffle, or they may be shaped to fit between two of the fins. The spring 40 is formed from a piece of round 45 spring wire in the embodiment shown but obviously may take other forms.

In the form of engine illustrated a considerable space exists between the rocker boxes on each individual engine. In order to prevent a free 50 passage of air through this space the V shaped baffles 28 and 30 are disposed therein and con- 55

nected with the cowl. These baffles might be flat plates formed with the proper contour but are illustrated as a sheet of metal formed into a V shape trough and tapered to a point toward the front of the cowl.

Figure 4 shows a modification of the means for holding the baffles between the cylinders and comprises a turnbuckle 44 connected with the baffle 24 at 46 and with the baffle 26 at 48. The turnbuckle 44 is adapted to force the points 46 and 48 apart and thus force the baffles 24 and 26 to their position between the cylinders. The baffles are otherwise similar to those shown in Figure 2.

15 The head baffles and the intercylinder baffles in effect form a partition which separates the engine and cowl into a front section and a rear section. Due to movement of the engine and cowl through the air or to the propeller thrust or 20 both it appears probable that increased pressure is created in the front section and a reduced pressure is created in the rear section of the engine and cowl. This increased pressure difference causes an increase in the velocity of the 25 air over the fins and probably causes a greater rate of heat exchange, although the quantity of air that is passed under the cowl and through the engine is probably less than that in an engine not provided with the baffles.

30 The installation of the pressure baffles reduces the quantity of air flowing through the cowl and thereby permits the use of a ring cowl of improved stream line shape having an air inlet opening and an air outlet opening of less extent 35 than the ring cowls used on unbaffled engines. The reduction in the air inlet opening permits a more pronounced curvature and improved air flow at the nose of the cowl and the reduction in the outlet opening eliminates a large portion of 40 the eddy currents and turbulence at the cowl trailing edge. This improved cowl shape is an important factor in reducing the drag of the cowled engine.

45 It is to be understood that the invention is not limited to the specific embodiment herein illustrated and described but may be used in other ways without departure from its spirit as defined by the following claims.

I claim:

1. Means for decreasing the drag of an air-cooled radial engine having heat radiating fins and increasing its heat radiating properties comprising a cowl of substantially ring form enclosing the entire finned area of said engine and 55 extending with diminishing size in the direction of travel of said engine said cowl being open in front and in back, and baffles between the cylinders of said engine, substantially completely closing the space between said cylinders except 60 between the individual cooling fins.

2. In a multicylinder aircraft engine of the air-cooled radial type, having the cylinders arranged in two parallel planes with the cylinders of one plane arranged between the cylinders of the other 65 plane, said cylinders having heat radiating fins, a cowling of substantially ring form arranged to completely encircle said engine, a plurality of baffles mounted on said engine to form with said engine a partition in said cowl, so that the air forced under said cowl by relative motion of the engine and the surrounding air is forced to pass between individual cooling fins in passing from 70 one side of the partition to the other.

3. A radial engine, comprising a plurality of

cylinders radially arranged around a common center line with some of the cylinders axially spaced from others, a drag reducing ring cowl arranged around the entire group of cylinders, fins on the cylinders, means for further reducing the drag of said engine and cowl comprising baffles arranged between said cylinders, said baffles following substantially the contour defined by outermost portions of said engine fins so as to substantially close the space between the cylinders except the space between the individual fins.

4. Means for holding baffles in position between the cylinders of a multicylinder engine having cylinders arranged in a plurality of parallel planes comprising in combination baffles having portions contacting with the engine, a toggle fastened at one end to one baffle and at the other end to another baffle and adapted to force the baffles apart and into place between the cylinders.

5. Means for holding baffles in position between the cylinders of a multicylinder engine having cylinders arranged in a plurality of parallel planes comprising, in combination, baffles having portions contacting with the engine, means between two of the baffles adapted to separate the baffles and urge them into position between the cylinders.

6. Means for decreasing the drag of an air-cooled radial engine having heat radiating fins, which comprises a drag reducing cowl of substantially ring form open at the front and rear and encircling the engine, and means substantially completely blocking the passage of air past said engine under the cowl except between the individual heat radiating fins.

7. Means for decreasing the drag of a radial air-cooled engine having a propeller rotating adjacent thereto which comprises a non-rotatable cowl of substantially ring form encircling the entire finned area of said engine with the leading edge of said cowl in front of the engine cylinders, said cowl being open at the front and rear, one of said openings being between the propeller and the engine, baffles adjacent the engine cylinders adapted to restrict the passage of air under said cowl substantially to the cross-sectional area between the cooling fins of each cylinder, said baffles acting to increase the pressure difference between the front and rear of said cylinders created by relative motion of the cowl encircled engine and the surrounding air.

8. Means for decreasing the drag of a radial air-cooled engine having a propeller rotating adjacent thereto which comprises, a stream line cowl of ring form fixed to said engine and entirely enclosing the finned area thereof with the leading edge of said cowl in front of the cylinders of said engine, said cowl having a rear opening and having a front opening between said engine and said propeller adjacent to the hub of said propeller, and baffles adjacent to the engine cylinders extending from the interior surface of said cowl to said engine and between adjacent surfaces of said cylinders to restrict the passage of air through said cowl to the air flowing between adjacent cooling fins on said cylinders, to bring the air entering the front opening of said cowl to a substantial standstill with respect to said cowl to provide an air pressure reservoir which distributes cooling air equally to all of said cooling fins and guides external air smoothly over the nose of said cowl.

ALBERT LEWIS MACCLAIN.
